UNITED STATES PATENT OFFICE.

JAMES A. CONNELL, OF PITTSTON, PENNSYLVANIA.

SMOKE AND GAS CONSUMING FIRE BOX FOR LOCOMOTIVES.

Application filed July 11, 1925. Serial No. 43,014.

To all whom it may concern:

Be it known that I, JAMES A. CONNELL, a citizen of the United States, residing at Pittston, in the county of Luzerne and State of Pennsylvania, have invented certain new and useful Improvements in Smoke and Gas Consuming Fire Boxes for Locomotives, of which the following is a specification.

The present invention appertains to an improved smoke and gas consuming fire box for locomotives, and has for its principal object to provide a structure of this nature which will consume far less fuel than the ordinary structures now in common use.

Another very important object of the invention is to provide a structure of this nature having improved features whereby a more perfect combustion of the fuel is obtained, thereby consuming the smoke and gas which is utilized as this fuel.

Another important object of the invention is to incorporate an improved fire box structure in a locomotive boiler so as to eliminate numerous unnecessary pipes, elbows, and the like which are used in the ordinary conventional construction.

A still further very important object of the invention is to generally improve upon a boiler structure of this nature by providing an exceedingly simple construction which may be manufactured at a low cost, one which is strong, durable, thoroughly reliable and efficient in use, and otherwise very well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a rear elevation of my improved structure,

Figure 2 is a longitudinal vertical section thereof taken substantially on the line 2—2 of Figure 1,

Figure 3 is a transverse vertical section therethrough,

Figure 4 is an enlarged detail section showing a modification,

Figure 5 is an enlarged detail section

through one of the upper headers and the wall resting thereon, and.

Figure 6 is a longitudinal vertical section through the device similar to Figure 2, but showing the modification shown in Figure 4.

Referring to the drawing in detail it will be seen that the boiler includes the usual casing 5 having disposed in the rear portion thereof a crown sheet indicated generally by the letter A, and including a crown top 6, sides 7, rear plate 8, and the front plate 9 which forms a flue plate for receiving a plurality of flues 10. A grate supporting structure is indicated generally by the numeral 11, and includes grates 12 of ordinary constructions which are disposed a distance 65 to the sides of the longitudinal dimension of the grate supporting structure. The crown sheet A, the grate supporting structure and the front walls 20' confine the fire box. Below the grate supporting structure 70 there is a suitable ash pit 13.

The grate supporting structure 11 is horizontally disposed. On this grate supporting structure adjacent the inner sides of the grates 12 there are vertically disposed two water grates indicated generally by the letters B. Each water grate B includes an upper header 15, and a lower header 16 which are connected by vertically disposed S-shaped tubes 17. If desired, these water 75 grates may be raised from the grate supporting structure 11 by building a brick wall under the lower header upon the grate supporting structure. The upper headers 15 communicate with the rear end of the boiler 80 through the rear plate 8, and cleaning plugs 19 are provided in the rear of the casing 5 aligned with the upper headers. It is apparent that by taking out these plugs repairs 85 may be made in the structure, or the upper headers may be cleaned. The space between the water grates and the space between walls 20 built thereabove to the top 6 of the crown sheet A form the combustion chamber of the fire box. The upper headers are pref- 90 erably flattened as is indicated at 21 in order that the walls 20 may be built thereon. These walls 20 may be reinforced if desired. A plurality of plugs 23 are provided in the upper headers 15 in order that access may 95 be had to the interior of the tubes 17 for

obvious reasons. The lower headers 16 extend through the sheet 9 to communicate with the front of the boiler. The water, therefore, will circulate downwardly in the boiler among the flue tubes 10, through the lower headers 16, upwardly through the S-shaped tubes 17, through the upper headers 15, into the rear end of the boiler.

The fire box has a pair of upper passages 10, 25 therein so that the fuel may be thrown thereinto, and doors 26 are associated therewith. Passages 27 communicate with the bottom portions of the fire box and have doors 28 associated therewith. A peep passage 29 is provided for the combustion chamber and has a door 30 associated therewith.

Plugs 31 are provided in the back sheet of the casing 5 in alignment with the lower headers 16. The front end of the lower headers are plugged as is indicated at 32. Plugs 34 are provided in the front portions of the boiler in order that the lower headers may be clean. A baffle plate 35 is provided to the front of the fire box a distance from the sheet 9 and the walls 20, and is spaced from the top 6, and sides 7 of the crown A. This distributes the heat so that it will be evenly divided among the flue tubes 10.

A plurality of draft tubes 37 extend through the sides of the casing 5 and through the sides 7 of the crown sheet A. It will thus be seen that the gas and smoke 35 cannot escape from above the fire on the grates 12, but must pass through the fuel and through the water grates, that is through the flame of the fire and be consumed. Thus the smoke and gases are 40 utilized as fuel.

Referring now particularly to the modification shown in Figure 4, it will be seen that the lower headers 16' are provided at their rear ends with reduced extensions 38, 45 thereby forming shoulders at 39. These extensions 38 terminate exteriorly of the casing 5, and plugs 40 are provided in the ends thereof, thereby doing away with the necessity of using two plugs 31 and 32 as described with the preferred embodiment.

It is thought that the construction, operation, utility, and advantages of this invention will now be clearly understood without a more detailed description thereof. The 55 present embodiments of the invention have been disclosed merely by way of examples, since in actual practice they attain the features of advantages enumerated as desirable in the statement of the invention, and the 60 above description.

It is apparent, however, that numerous changes in the details of construction, in the combination and arrangement of parts may be resorted to without departing from the

spirit or scope of the invention as herein-after claimed or sacrificing any of its advantages.

Having thus described my invention, what I claim as new is:

1. In a locomotive boiler, a plurality of flue tubes in the forward portion thereof, a crown sheet including a front wall receiving the flue tubes, a pair of sides, and a rear sheet, thereby forming a fire box, a grate supporting structure in the bottom of the fire box horizontally disposed, grates in the supporting structure, one to each side of the median longitudinal dimension thereof, a pair of water grates disposed vertically in the fire box and extending longitudinally thereof in spaced relation to form a combustion chamber therebetween, walls rising from the water grates to the top of the crown sheet, and a plurality of draft tubes 75 communicating the sides of the fire box with the exterior, and a baffle plate disposed in the fire box to the front of the combustion chamber and to the rear of the plate supporting the ends of the flue tubes.

2. In a locomotive boiler, a plurality of flue tubes in the forward portion thereof, a crown sheet including a front wall receiving the flue tubes, a pair of sides, and a rear sheet, thereby forming a fire box, a grate supporting structure in the bottom of the fire box horizontally disposed, grates in the supporting structure, one to each side of the median longitudinal dimension thereof, a pair of water grates disposed vertically in the fire box and extending longitudinally thereof in spaced relation to form a combustion chamber therebetween, walls rising from the water grates to the top of the crown sheet, and a plurality of draft tubes 90 communicating the sides of the fire box with the exterior, and a baffle plate disposed in the fire box to the front of the combustion chamber and to the rear of the plate supporting the ends of the flue tubes.

3. In a locomotive boiler, a plurality of flue tubes in the forward portion thereof, a crown sheet including a front wall receiving the flue tubes, a pair of sides, and a rear sheet, thereby forming a fire box, a grate supporting structure in the bottom of the fire box horizontally disposed, grates in the supporting structure, one to each side of the median longitudinal dimension thereof, a pair of water grates disposed vertically in the fire box and extending longitudinally thereof in spaced relation to form a combustion chamber therebetween, walls rising from the water grates to the top of the crown sheet, and a plurality of draft tubes 95 communicating the sides of the fire box with the exterior, and a baffle plate disposed in the fire box to the front of the combustion chamber and to the rear of the plate supporting the ends of the flue tubes.

3. A locomotive boiler; wherein said locomotive boiler includes a crown sheet having a rear portion, a grate supporting structure disposed horizontally in the bottom of the crown sheet; comprising a water grate disposed vertically from the grate supporting structure and extending longitudinally thereof and including a lower header resting on the grate supporting structure, said lower header being reduced at its rear end and extending through the rear end of the boiler, and a plug in said reduced extension.

In testimony whereof I affix my signature

JAMES A. CONNELL.
